UNITED STATES PATENT OFFICE.

JAMES M. CONNER, OF GREENVILLE, NEW JERSEY.

DESIGN FOR A FONT OF PRINTING-TYPES.

Specification forming part of Design No. 11,184, dated May 6, 1879; application filed April 10, 1879.
[Term of patent 7 years.]

To all whom it may concern:

Be it known that I, JAMES M. CONNER, of Greenville, Hudson county, New Jersey, have invented and produced a new and original Design for a Font of Printing-Types, of which the following is a specification.

The nature of my design is shown in the accompanying typographic impression, to which reference is made.

It consists of an ornamental letter shaded upon the right and bottom by a heavy line, followed by a lighter one.

The up-and-down portions of the letters are continued at top and bottom in the case of all the letters save the C, G, O, and Q, and form the terminations having inclined sides and spur-like projections, as shown. The up-and-down portions of the letters are also curved about centrally, as shown, and within these curved portions are received the oval-like figures hereinafter mentioned.

The faces of the letters are shaded by a series of horizontal lines parallel with the outline of the letter within which they are placed, and ornamented by a series of oval-like figures, which, in the case of the A and H, are connected together by a light horizontal line, and in the case of the X and Y are flattened out.

The letters are further ornamented at top and bottom by the rhomboidal ornaments, the letters being concaved to receive them.

In the symbols & $ £, the figures, and lowercase, the character of the design is preserved.

Having now described my invention, what I claim as new is—

The design for a font of printing-types, substantially as shown and described.

JAMES M. CONNER.
